UNITED STATES PATENT OFFICE.

CLARENCE E. JENKINS, OF KEENE, NEW HAMPSHIRE.

DESIGN FOR A GARDEN-URN.

55,864.

Specification for Design.

Patented July 20, 1920.

Application filed October 27, 1919. Serial No. 333,848. Term of patent 14 years.

To all whom it may concern:

Be it known that I, CLARENCE E. JENKINS, a citizen of the United States, residing at Keene, in the county of Cheshire, State of New Hampshire, have invented a new, original, and ornamental Design for a Garden-Urn, of which the following is a specification, reference being had to the accompanying drawing, forming part thereof, wherein—

Figure 1 is a front view showing my design; and

Fig. 2 is a side view of the same.

I claim:—

The ornamental design for a garden urn, as shown.

In testimony whereof, I affix my signature.

CLARENCE E. JENKINS.
